[57] CLAIM

The ornamental design for site furniture in the form of an ash
urn, as shown and described.

DESCRIPTION

FIG. 1 is a perspective view of site furniture in the form of
an ash urn showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof; and,
FIG. 7 is a left side elevation view thereof.

The broken line showing of the legs and the container in
FIGS. 1-4 and 6-7 and the bottom bars in FIG. 5 are for
illustrative purposes only and form no part of the claimed
design.
